GAETAN P. LIEVRE, OF PARIS, FRANCE.

LATCH.

Application filed October 2, 1923, Serial No. 666,126, and in France October 13, 1922.

This invention relates to latches for doors, windows, panels, or the like, whether hinged or sliding.

A main object of the present invention is to prevent chattering of closed windows in doors of moving vehicles, particularly automobiles.

Another object of the invention is to provide a latch in the nature of a wedge which automatically operates as the door, panel, window, or the like is closed.

Another object is to provide a latch in the nature of a wedge which is also resilient, so that as the door is latched on the completion of a closing movement there is no jarring action which might damage or shatter glazed portions of the moving member.

Another object is to provide a latch of the nature above referred to which automatically regains its initial position when the door is in an open position, so that it is ready for operation at the next closing movement of the door.

Another object of the invention is to provide a wedging member the contour of which, when in contact with the door, corresponds to the closing edge of the door, so that a prolonged contact face is provided, thereby eliminating any possibility of a rocking movement between the wedging member and the door, or the like.

A still further object is to provide a wedging member having a contour corresponding to that of the closing edge of the door and extending for a height equivalent to the height of the door, so that by reason of the coinciding contact faces of the door and wedging member, a substantially airtight joint is provided.

In the accompanying drawings is illustrated, by way of example, preferred forms of the present invention in its application to hinged doors and to sliding windows, or the like.

In these drawings:

Fig. 1 is an elevation of the rebate of a door, provided with the latching finger which forms the subject-matter of this invention; Fig. 2 is a section on the line $z-z$ of Fig. 1; Fig. 3 shows a modification of Fig. 1; Fig. 4 shows a second modification; Fig. 5 is a section on the line $y-y$ of Fig. 4; Fig. 6 shows a modification of the device shown in Fig. 2; and Figs. 7 and 8 show the application of the device which forms the

subject-matter of this invention to a sliding window.

In Fig. 1, the rebate 1 of the door has formed in it a recess 2, in which a wedging member 4 in the form of a cam and provided with a finger 5 is adapted to rock on a pivot 3, as is shown in Fig. 2. When the door is open, the member 4 occupies the position 4¹ shown by dot and dash lines, under the action of the spring 6, and its finger is at 5¹ and its spring at 6¹. The edge face of the glazed frame 7 of the door is of curved section and its profile corresponds to the profile of the cam or wedging member 4. This face terminates at one side in an edge 8 corresponding to the finger 5.

When the door is closed, the glazed frame 7 accompanies the door and rocks on its pivot, following the course or path indicated by the arrow F.

At the end of the path the edge 8 of this glazed frame strikes against the finger 5, causes the cam 4 to rock on its pivot, compresses the spring 6, and brings said cam into the position shown in full lines in Fig. 2, which is the position in which the cam corresponds exactly to the profile of the edge of the frame, thus latching the frame and rendering it immovable, as shown in the figure.

In consequence of the special shape of the cam, the frame 7 is latched and cannot rock in the reverse direction to that indicated by the arrow F, or chatter due to vibration or variable wind pressure, being also clamped laterally between the pivot on which it rocks and the cam 4 which renders it absolutely immovable.

On applying effort to open the door, the frame 7 carried along with it becomes released of itself, and the spring 6 will bring the cam back to the position 4¹ again, to be ready again the instant the door is closed.

It must be understood that instead of a single wedging member or cam only, any number of such cams may be mounted along the rebate 1, (three in the case of Fig. 1) and the edge of the frame 7 will consequently be profiled to the level of each cam or over the whole of its length.

I may also in place of a number of cams use a cylinder 9, extending over the entire height of the rebate, having the same section as the cam 4, rocking on a pivot 3, and exercising over the whole of its height the

same function as the cam or cams in Fig. 1 and drawn back like them by spring tongues 10, or any other suitable spring device.

I may also, as shown in Fig. 5, carry out 5 my invention by means of a simple finger 11 instead of a cam, this finger engaging in a suitably shaped recess 16 in the edge face of the frame. The lateral clamping action 10 which the cam produces by reason of its shape or outline is replaced in this case by the action of a spring 15 which thrusts the finger 11 against the bottom of the recess 16 as will be explained hereinafter.

The said finger 11, which may be of any 15 suitable form, is mounted in the recess 2 in the rebate 1 to turn about a vertical pivot 12, but this pivot, instead of being fixed to the rebate as in the example above described, is carried by a member 13 which is movable 20 laterally and is guided in a recess 14 formed for this purpose in the rebate, and is constantly thrust outwards, that is to say, towards the right in the case of Fig. 5, by the above-mentioned spring 15 which may be a 25 coiled or other spring. When the door is opened, the finger 11 occupies, under the action of the spring 15, the position 11¹. The recess 16 in the edge face of the glazed frame 7 is cut either to the height of the 30 finger 11, or over the whole of its height, in the form of a gutter.

The instant the door is closed, the finger 17 forming the edge of the recess or gutter 16 strikes against the finger 11, and causes 35 it to rock upon its pivot. The said finger 11 engages in the gutter 16 and by means of the spring 15 which thrusts it down to the bottom of this gutter, corresponds exactly to the shape thereof, and produces the lateral clamping of the glazed frame 7 and consequently renders it absolutely immovable.

It must be understood that instead of a 45 single finger 11 I may employ a number of such fingers arranged over the whole of the height of the rebate 1. Each of these fingers will be provided with its own adjustable pivot and its own thrust spring, or on the other hand, all the fingers may be mounted 50 on the same pivot carried by one or more sliding members and be provided with a single spring mechanism for producing the lateral thrust.

I may also employ, as shown in Fig. 4, a 55 cylinder 18 having as its profile the profile of the finger 11 and mounted on and rocking on a pivot 12 carried by a certain number of sliding members 13 attached to springs 15, this cylinder exercising over the whole 60 of its height the same function as the finger 11.

The modification shown in Fig. 6 differs 65 from the device hereinbefore described and shown in Fig. 2, by the addition to the wedging member or cam, which is desig-

nated 44 either at the front or at the rear thereof, of a second finger 19 which, when the door is closed, will correspond exactly to the external face of the movable frame 77, as shown. The second finger will be, preferably, of greater length than the finger 55, which latter corresponds to the finger 5 in Fig. 2.

By means of this second finger 19 a better 75 securing of the movable frame 77 is obtained, as said frame is not liable to be subjected to any torsion capable of breaking the glass or spoiling the frame, as might happen in certain cases if the frame were 80 violently returned to its latching position.

As has been stated above, the edge face 85 of the frame 77 is suitably shaped so as to correspond exactly with the form of the cam and its fingers. It will be of advantage to give to the external portion of said edge 90 face, against which the finger 19 bears, the form of a slight projection 77¹, the profile of the finger 19 being suitably curved in consequence so as to correspond exactly to this projection, as is shown in Fig. 6. In this 95 case the finger 19 acts really as a hook and might also be replaced by a hook.

Instead of being made in the form of a cam, the member 44 may be equally well 100 constituted by a member of circular section 105 suitably mounted off centre and exercising the same function.

This eccentric will be provided, it must be understood, with one or more fingers, according as the arrangement or construction 110 shown in Fig. 2, or that shown in Fig. 6, is adopted.

All that has been stated hereinbefore 115 about the arrangement of one or more wedging members or cams along the rebate of the door mounted on the same pivot, or on different pivots, and about the provision of a single member having the same section 120 as the cam and extending over the whole height of the rebate, or over a portion of this height may, it must be understood, be repeated here.

In like manner the retracting spring 66 may be replaced by any other spring device, 125 as for example, a coiled or similar spring acting on the pivot 33 and adapted to bring back the member 44 to the position 44¹ shown in dot and dash lines, when the frame 77 is open.

Hitherto only the latching of rocking 130 glazed frames has been considered, but the device which forms the subject-matter of the present invention applies equally well to the latching of sliding glazed frames or windows, such as those which are commonly used in the bodies of automobile vehicles, in railway carriages, and other vehicles.

Figs. 7 and 8 show, by way of example, 135 a constructional form of the latching device for such sliding glazed frames.

20 denotes a panel which may be fixed or movable, and in which a glazed frame 21 slides, said frame being adapted to be moved into position at the upper part of the panel, 5 as is shown in Fig. 8.

In these sliding frame arrangements, the glazed frame, when it is in place, is subjected to the concussions of the vehicle.

In order to latch it, I use a wedging member 22 similar to the cam 4 employed for the arrangement shown in Fig. 2, having preferably the profile shown in Figs. 7 and 8 and having a flat portion 23 and a finger 24, the flat portion and the edge of the finger 24 constituting the sides of a right angle.

This member is adapted to rock on a pivot 25 mounted in the upper part of the recess in the panel 20. A retracting spring 26 tends to bring back the cam 22 to the position shown in Fig. 7.

When the glazed frame or window is raised, its upper edge 27 will strike against the finger 24 and cause the member 22 to rock, thus compressing the retracting spring. The upper edge 27 thus becomes seated, when the window is completely raised (see Fig. 8), in the angle formed by the finger 24 and the flat part 23, and the window will then be rendered absolutely immovable by the action of the cam or eccentric 22.

I may, it must be understood, mount along the upper edge of the panel 20 one, two, or a greater number of latching members such as 22, and I may also use a cylinder having the same section and extending over the whole length of this upper edge or over only a portion of this length.

The retracting spring device may be of any other type than the one described. The eccentric may also be of any suitable form that will allow it to correspond exactly to the form which it has been thought well to give to the edge 27, that is, in intaglio, or in relief.

Furthermore, in order to avoid strain on the hinges at the moment of closing, I may provide an elastic device constituted either by coiled springs, or by flat or other springs, so that the whole may be subjected to slight flexion the instant the window comes into contact with the cam. This device will also act to automatically take up the slack produced by wear.

It must be distinctly understood that the various arrangements which have just been described are given by way of simple examples only, and that I reserve to myself the right to vary the constructive arrangements without departing from the scope of my invention.

Again, the device which forms the subject-matter of the present invention may, in all its constructional forms, be applied as I have already said, to all other uses than the latching of automobile windows. It may

also be constructed and used for the latching of any movable device, such for example, as a folding door, a casement window, or the like.

I claim:—

1. Automatic means for latching and unlatching a rigid, plane closure member within an open frame, comprising a wedging member pivotally mounted within the frame and adapted to be struck and turned about its pivot by the closure member as the latter reaches closing position, so as to bring a wedging portion of the wedging member into binding engagement with the edge face of the closure member; means being provided to oppose lateral movement of the closure member under such wedging action.

2. Automatic means for latching and unlatching a rigid, plane closure member within an open frame, comprising a pivot carried by the frame, and disposed therewithin in the plane of the closure member when the latter is in closed position, and a cylindrical member eccentrically mounted on said pivot and adapted to be struck and turned about the pivot by the closure member on reaching closing position, so as to bring a wedging portion of the wedging member into binding engagement with the edge face of the closure member; means being provided to oppose lateral movement of the closure member under such wedging action.

3. Automatic means for latching and unlatching a rigid, plane closure member within an open frame, comprising a pivot carried by the frame and disposed therewithin in the plane of the closure member when the latter is in closed position, a cylindrical member eccentrically mounted on said pivot, and a projection on the cylindrical member adapted to be struck by the closure member on reaching closing position so as to rotate said cylindrical member about the pivot and thereby bring a wedging portion thereof into binding engagement with the edge face of the closure member; means being provided to oppose lateral movement of the closure member under such wedging action.

4. Automatic means for latching and unlatching a rigid, plane closure member within an open frame, comprising a pivot carried by the frame and disposed therewithin in the plane of the closure member when the latter is in closed position, a cylindrical member eccentrically mounted on said pivot, and a projection on the cylindrical member; the portion of said cylindrical member adjacent said projection having a contour corresponding to the edge configuration of the closure member, so that as said closure member reaches closing position it strikes the projection and rotates the cylindrical member about its pivot into such a position that the said portion thereof adjacent the projection is brought into wedging en-

gagement with the edge face of the closure member, while the projection itself fits snugly against the adjacent face of said closure member.

5. 5. Automatic means for latching and unlatching a rigid, plane closure member within an open frame, comprising a pivot carried by the frame and disposed therewithin in the plane of the closure member when 10 the latter is in closed position, and an eccentric mounted on the pivot and having a projection which is adapted to be struck by the closure member on reaching closing position so as to rotate the eccentric about said pivot 15 and thereby bring a wedging portion thereof into binding engagement with the edge face of the closure member.

6. Automatic means for latching and unlatching a rigid, plane closure member within 20 an open frame, comprising a wedging member pivotally mounted within the frame and adapted to be struck and turned about its pivot by the closure member as the latter reaches closing position so as to bring a wedging portion of the wedging member 25 into binding engagement with the edge face of the closure member, and resilient means for retracting the wedging member to normal position when the closure member is 30 turned to an open position.

7. Automatic means for latching and unlatching a rigid, plane closure member within an open frame, comprising a pivot carried by the frame and disposed therewithin in 35 the plane of the closure member when the latter is in closed position, an eccentric mounted on the pivot and having a projection which is adapted to be struck by the closure member on reaching closing position 40 so as to rotate the eccentric about said pivot and thereby bring a wedging portion thereof into binding engagement with the edge face of the closure member, and resilient 45 means for retracting the eccentric to normal position when the closure member is returned to an open position.

8. Automatic means for latching and un-

latching a hinged door within an open frame, comprising pivots on the opposite side of the frame from the door hinges, a 50 cylindrical member eccentrically carried by said pivots, and a projection on the cylindrical member adapted to be struck by the door on reaching closing position so as to rotate said cylindrical member into a position in which a wedging portion thereof is brought into binding engagement with the edge face of the door.

9. Automatic means for latching and unlatching a hinged door within an open 60 frame, comprising pivots on the opposite side of the frame from the door hinges, an eccentric on each pivot, and a projection on each eccentric; said projections adapted to be struck by the door on reaching closing 65 position so as to rotate the eccentrics about their pivots and thereby bring a wedging portion of each eccentric into binding engagement with the edge face of the door.

10. Automatic means for latching and unlatching a rigid, plane closure member within an open frame, comprising an eccentric pivotally mounted within the frame and having a rolling surface, and a pair of fingers on the eccentric limiting such surface at opposite ends; one finger adapted to be struck by the closure member on reaching closing position so as to rotate the eccentric about its pivot and thereby bring the rolling surface thereof into binding engagement with the edge face of the closure member, the other finger adapted to fit snugly against the adjacent side face of said member.

11. Automatic latching and unlatching means, according to claim 10, in which the second-named finger has a length appreciably greater than the first-named finger, so as to prevent the closure member from passing beyond the pivot of the eccentric.

In testimony whereof I have signed this specification.

GAETAN LIÈVRE.
